UNITED STATES PATENT OFFICE.

STERLING H. CAMPBELL, OF ST. LOUIS, MISSOURI.

WEDGE FOR JOURNAL-BEARINGS.

1,204,405.

Specification of Letters Patent. Patented Nov. 14, 1916.

Application filed February 16, 1916. Serial No. 78,753.

To all whom it may concern:

Be it known that I, STERLING H. CAMPBELL, a citizen of the United States of America, residing at the city of St. Louis, State 5 of Missouri, have invented a certain new and useful Wedge for Journal-Bearings, of which the following is such a full, clear, and exact description as will enable any one skilled in the art to which it appertains to make and 10 use the same, reference being had to the accompanying drawings, forming part of this specification.

My invention relates to a wedge for journal bearings, and more particularly to journal 15 bearings of railway cars.

The object of my invention is to provide simple and effective means for removing the wedge from its position in the journal box.

In the accompanying drawings, which 20 illustrate some forms of my wedge made in accordance with my invention with so much of a railway journal bearing as is necessary to describe my invention, Figure 1 is an isometric projection showing 25 my preferred form of wedge; Fig. 2 is a longitudinal section through the forward end of the wedge, the wedge being shown in position in the journal box; Fig. 3 is a front view of the parts shown in Fig. 2; 30 Fig. 4 is a front view of the wedge, showing a slight modification; Fig. 5 is a section taken on the line 5—5 of Fig. 4; Fig. 6 is a top plan view of the front end of the wedge shown in Fig. 4; Fig. 7 is a front 35 view of the wedge showing a still further modification; Fig. 8 is a section taken on the line 8—8 of Fig. 7; Fig. 9 is a top plan view of the front end of the wedge shown in Fig. 7.

Like marks of reference refer to similar parts in the several views of the drawings.

10 is a railway journal box in which is the end 11 of the axle. The journal box 10 is provided with a bearing face 12 adapted to 45 bear on the top of the wedge. It is also provided with bearing faces 13 for limiting the lateral movement of the wedge, and with dependent flanges 14 for preventing the forward movement of the wedge when it is in 50 its normal position in the box. Only one of the bearings 13 and flanges 14 is shown in Figs. 2 and 3 of the drawings, but it will be understood that one of the bearings and flanges is arranged at each side of the journal 55 box.

Referring first to Figs. 1, 2 and 3—15 represents a wedge adapted to bear upon the brass 16, which is not shown in detail, as it forms no part of the present invention. The wedge 15 is provided with lateral projections 17, adapted to bear against the bearing faces 13 of the box, and with a forwardly projecting wing 18, which is adapted to co-operate with the flanges 14 to prevent the withdrawal of the wedge when it is in its 60 normal position. The upper face 19 of the wedge 15 is slightly curved longitudinally, not only to allow it to accommodate itself to the varying positions of the box, but also to assist the removal of the wedge from the box. 70

In order to provide means for forcing the wedge downwardly so that the wing 18 may pass below the flanges 14 of the box, I provide in the forward end of the wedge a tool-way 20, which tool-way is preferably inclined as best shown in Fig. 1. This tool-way extends below the upper face of the wedge so that a tool may be readily inserted between the flanges 14, in order to force the forward end of the wedge downwardly. 75 Said movement of the wedge is facilitated by the curved form of its upper bearing face. In order to draw the wedge forwardly out of the box after it has been forced downwardly, I provide a shoulder 21, which is centrally located with respect to the tool-way 20. It will be evident that after the wedge has been forced downwardly a hook shaped tool may be used to co-operate with the shoulder 21 and draw the wedge forward 80 out of the box. 85

In Figs. 4, 5 and 6 I have shown a slight modification of my wedge. In this form the wedge is provided with a longitudinally curved upper face 19, as in the previously 90 described form. It is also provided with a tool-way 20. The shoulder 21 is, however, omitted, and, in order to draw the wedge forwardly, the tool-way 20 is extended laterally, as best shown at 22 of Fig. 6, so as to 100 provide a pair of shoulders 23, one arranged at each side of the tool-way 20.

The operation of this form of wedge is the same as that above described, except that in drawing the wedge out of the box the hook shaped tool co-operates with one or the other of the shoulders 23 at the side of the tool-way 20. 105

In Figs. 7, 8 and 9 I have shown a still further modification of my form of wedge. 110

In this modification both the shoulders 21 and 23 are omitted, and, in order to draw the wedge forwardly out of the box, I provide the wedge at the rear of the tool-way 20 with a recess 24 forming a shoulder 25 just at the rear of the tool-way 20. In this form of wedge the tool for drawing the wedge forwardly is engaged with a shoulder 25 at the rear of the tool-way 20.

10 In all of the forms of my wedge it will be evident that a tool can be readily inserted from the front of the box to engage with the inclined tool-way and force the wedge down out of contact with the upper face of 15 the box to allow the wing 18 to pass below the flanges 14, after which the tool may be engaged with a shoulder in order to draw the wedge forward out of the box, thus providing an easy and effective method of 20 moving the wedge from the box.

Having fully described my invention, what I claim as new, and desire to secure by Letters Patent of the United States is:

1. In a device of the class described, the 25 combination of a wedge and a journal box bearing thereon, said wedge having a tool-receiving recess formed in the outer edge of its upper surface, and tool-engaging means adjacent to said recess whereby the wedge

may be withdrawn longitudinally from the 30 box.

2. In a device of the class described, the combination of a journal bearing member, a wedge, and a journal box bearing on said wedge, said box being provided with a flange 35 for retaining the wedge against outward movement, and the wedge being provided with means on the outer edge of its upper surface situated back of the line of the flange for moving the wedge to a position to 40 pass said flange.

3. In a device of the class described, the combination of a journal bearing member, a wedge, and a journal box bearing on said wedge, said box being provided with a flange 45 for retaining said wedge against outward movement, and the wedge being provided with a tool-receiving recess in the outer edge of its upper surface and back of the line of the flange.

In testimony whereof, I have hereunto set my hand and affixed my seal in the presence of the two subscribing witnesses.

STERLING H. CAMPBELL. [L. S.]
